FIG. 1.

FIG. 2.

Inventor
Charles Rodin
by Herbert H. Jenner
Attorney

UNITED STATES PATENT OFFICE.

CHARLES RODIN, OF ISANTI, MINNESOTA.

DOOR-OPENER.

1,272,853.

Specification of Letters Patent. Patented July 16, 1918.

Application filed November 19, 1917. Serial No. 202,852.

To all whom it may concern:

Be it known that I, CHARLES RODIN, a citizen of the United States, residing at Isanti, in the county of Isanti and State of Minnesota, have invented certain new and useful Improvements in Door-Openers; and I do hereby declare the following to be a full, clear, and exact description of the invention, such as will enable others skilled in the art to which it appertains to make and use the same.

This invention relates to openers for double doors such as used on churches, garages, and various public buildings; and it consists in the novel construction and combination of the parts hereinafter fully described and claimed whereby both doors or door sections are constrained to open and close simultaneously. In the drawings, Figure 1 is a front view of the upper portion of a double door provided with an opener according to this invention. Fig. 2 is a plan view of the same.

The two doors or door sections 2 are connected to the door posts or frame 3 by means of any approved hinges 4, and these doors are arranged so that they move apart on their hinges on the same side of the door frame in the act of opening. One of the doors is provided with a handle 5, and any approved fastening devices are provided for holding the doors closed.

In order to constrain both doors to open simultaneously, a bracket 6 is secured to one of the door posts, and is provided with a forwardly projecting arm 7 which carries a pivot pin 8 which is arranged substantially in the same plane as the pivot pin of the adjacent hinge.

A lever 10 is provided and is pivoted on the pin 8, and is arranged above the level of the top of the door. One end of the lever 10 is straight, and is pivoted by a pin 14 to a link 12. The link 12 projects rearwardly of the lever and is pivoted at its other end to a pin 15 on the upper end of a bracket 16 which is secured to the adjacent door at a little distance from the axis of its hinge.

The other end portion of the lever is curved rearwardly. The other door has an anchor bracket 20 secured to it adjacent to the axis of its hinge, and projecting forwardly of it. This bracket has a flat top portion provided with a row of pivot holes 21 for adjustment purposes, and arranged parallel to the door. A coupling rod 22 is provided, and one end of it is connected to the curved end portion 17 of the lever by a pivot 24. The other end of the rod 22 is provided with a pivot 25 which engages with either of the holes 21 in the anchor bracket.

The full lines in Fig. 2 show the doors in their closed positions. When one door is pulled open by its handle, the various parts move to the positions shown in dotted lines, so that the doors are constrained to open simultaneously. Both doors also close simultaneously, and this construction is found to be a great advantage for garages, churches, and many other buildings which require to have wide door openings, and to have their doors opened with little loss of time.

What I claim is:

The combination, with a door frame, and two doors pivoted to the side portions of the door frame and both opening forwardly; of a supporting arm secured to one side portion of the door frame adjacent to the pivot of one door and projecting forwardly; a lever having its middle part fulcrumed on the said arm, said lever having a front end portion arranged substantially parallel to the said door when closed, and having a rear end portion which projects rearwardly toward the door frame, a link pivoted to the front end portion of the lever and to the said door, an anchor piece secured to the other door adjacent to its pivot, and a connecting-rod pivoted to the rear end portion of the said lever and to the said anchor piece and working crosswise of the said arm and to the rear of the fulcrum of the said lever.

In testimony whereof I have affixed my signature.

CHARLES RODIN.
